FOOD CUTTING MACHINE

Raymond Kieves, Winnipeg, Manitoba, Canada, assignor
to K-Tel International, Inc., Minneapolis, Minn.

Filed Oct. 4, 1971, Ser. No. 186,567

Term of patent 14 years

Int. Cl. D7—04

U.S. Cl. D7—155

Fig. 1

Fig. 2

Fig.3

Fig. 4

Fig.5

Fig. 6

Fig. 7

FIG. 1 is a front perspective view of a food cutting machine embodying my new design;

FIG. 2 is a rear perspective view of the food cutting machine;

FIG. 3 is a front view of the food cutting machine;

FIG. 4 is a side view of the food cutting machine;

FIG. 5 is a rear view of the food cutting machine;

FIG. 6 is a top view of the food cutting machine, it being understood that the surface pattern thereon is continuous over the top as in FIGS. 1 and 2; and

FIG. 7 is a bottom view of the food cutting machine.

I claim:

The ornamental design for a food cutting machine, as shown and described.
